United States Patent Office.

JOSEPH H. WINTERBOTTOM AND JAMES LORD, OF PHILADELPHIA, PENN
SYLVANIA.

Letters Patent No. 68,476, dated September 3, 1867.

IMPROVEMENT IN SPINNING-JACKS.

The Schedule referred to in these Letters Patent and making part of the same.

TO ALL WHOM IT MAY CONCERN:

Be it known that we, JOSEPH H. WINTERBOTTOM and JAMES LORD, both of Philadelphia, in the State of Pennsylvania, have invented a new and useful Improvement in Spinning-Jacks; and we do hereby declare that the following is a full and exact description of the construction and operation of the same, reference being had to the annexed drawings, forming part hereof, in which drawings—

Figure 1 is a perspective view of a portion of a spinning-jack showing the application of our improvement thereto.

Figure 2, an end elevation of the same.

Figure 3, a front elevation of the carriage and track, showing the race-pulley W.

The object of our improvement is to aid the spinner in winding the yarn on the bobbins, and to secure a more regular twist in the yarn.

To enable others skilled in the art to make and use our improvement, we will proceed to describe its construction and mode of operation.

In the drawings, A represents the floor of a mill; B and C the track upon which the carriage D (that part of the jack bearing the spindles) moves to and from the roller-beam. This roller-beam does not appear in the drawings, but it forms a well-known part of the jack-frame, of which the beams E, F, and G constitute the rear side. H is a shaft, with bearings at J and K; it carries two pulleys L and M, of which L is a fast and M a loose pulley, also a fast pulley N for the race-belt, which gives motion to the carriages and spindles. O is the starting-bar, which has a free sliding motion, as shown. It is caused to press in the direction of the arrows by mechanism not shown. It carries the fork P, by which the belt, which transmits power from the main shaft of the mill to the spinning-jack, is guided on and off the fast pulley L.

The parts thus far specified belong to spinning-jacks in general, and they are here described only to enable us more easily to point out the construction and mode of operation of our improvements. Thus:

We attach a small wheel, R, to the starting-bar O by passing a suitable stud through a slot in this bar, as shown. There is a nut, a, by screwing or unscrewing which this wheel R is held in the desired position. S is an upright bar, its upper end passing through a guide, as shown. It has attached to it rigidly, by set-screws or their equivalents, a projecting curved piece, T, which is intended to be kept in contact with wheel R. The lower end of the bar S is joined by a hinge to the lever U, which is supported at its middle by the stand V to which it is pivoted. X and Y are two adjustable slides curved on one side and grooved on the other. They are placed on the lever U, one on each side of the stand V, and fastened in place each by a set-screw. The slide X is intended to be placed at such a point on the lever U that the race-pulley W shall come in contact with it at or about the time the carriage is started inwards. The slide Y may be placed so that the race-pulley shall come in contact with it, and thus at such point as the spinner may desire to stop the inward motion of the carriage.

The operation of our improvement is as follows: When the carriage D is out the spinner starts it in as usual, and the race-pulley W at once comes in contact with the slide X, and thus depresses the outer end of the lever U, and correspondingly elevates the inner end of the same lever, forcing the projection T against the wheel R, which moves the starting-bar O, causing the fork P to guide the driving-belt partly on to the fast pulley L, and thus assist the spinner to turn the spindles and wind up the yarn. The carriage continuing its movement inwards the race-pulley W comes in contact with the slide Y, which depresses the inner end of the lever U, causing the fork P to throw the driving-belt on to the loose pulley M, and thus stop the movement of the jack.

Having thus described our invention, we claim, and desire to secure by Letters Patent—

1. The lever U, adjustable slides X and Y, bar S, curved projection T, and wheel R, in combination with a spinning-jack, in the manner and for the purpose substantially as shown and described.
2. The bar S, curved projection T, and wheel R, in combination with the starting-bar O of a spinning-jack, substantially as described.

JOSEPH H. WINTERBOTTOM,
JAMES LORD.
